UNITED STATES PATENT OFFICE.

OTTO BOTHE, OF STEGLITZ, NEAR BERLIN, AND LUDWIG SCHIFF, OF BERLIN,
GERMANY.

ELECTRIC SOUND-REPRODUCING DEVICE.

Application filed June 6, 1924. Serial No. 718,303.

To all whom it may concern:

Be it known that we, OTTO BOTHE, residing at Steglitz, near Berlin, Germany, and LUDWIG SCHIFF, residing at Berlin, Germany, have invented certain new and useful Improvements in Electric Sound-Reproducing Devices; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to electrical devices for reproducing sound and particularly to devices of this kind adapted for use in acoustical cinematography (speaking films) and in the electrical transmission to a distance of concerts, speeches, lectures or the like without distortion of the original sounds and without extraneous noises. To accomplish this a fluid current such as a current of gas, air or steam by whose pressure fluctuations sound waves of any desired strength can be produced, is employed.

This invention differs from known devices of this kind in that the acoustical control of the fluid current used for the production of sound is not performed by a mechanical valve which has inertia, but by a purely electrical agency in the form of an electric field, the fluid current being electrically charged for the contemplated purpose. The invention enables a pure reproduction of original sounds to be obtained, extraneous sounds and changes of timbre being avoided because all influences that tend to falsify the characteristics of the original sound, such as eddies, disturbing natural frequencies, damping and cutting out of high harmonics by mechanical, electrical or magnetic inertia, are eliminated. Hence all sounds, even the most complicated ones, can be quite faithfully reproduced, even when they are amplified far beyond their natural loudness in order to make them audible to a very large audience. A fluid in the form of gas or steam can be charged with electricity in different ways. Air for example can be ionized in a known manner by ultraviolet light, Röntgen rays, radioactive substances, heating to a high temperature etc. A particularly simple and effective electrifying means for steam is

an Armstrong steam electrifying machine adapted for the purposes contemplated by this invention.

The production of an electric field by talking currents (by which, in this specification, is meant electric currents in general whose fluctuations of strength and potential correspond to the rhythm of the sounds to be reproduced) may be effected by causing the talking currents, which may be amplified by one or more thermionic valves or suitable amplifiers, to charge a perforated metallic body such as a sieve, grid or the like. The electrically charged fluid is controlled by being conducted through the perforated metallic body.

The talking currents which produce the said electrical field may be produced by a device located near the sound producer or combined therewith, as for example with the aid of a plastic phonogram (phonographic record) which controls one or both of the electrodes of an electric discharge gap or an electrode placed between the two electrodes of a discharge gap.

The invention is illustrated by way of example in the drawing, in which 1 is the boiler of an Armstrong steam electrifying machine, and 2 designates electrical heating elements placed in the interior of the water container. The heating elements 2 are heated by a current which is regulated by an automatic device hereinafter more fully described so that the steam pressure is always maintained constant. The steam produced is conducted through a short pipe connector 3 into a condensing vessel 4 provided with cooling ribs, the steam being thus caused to travel past the condensed water 5 that forms in the vessel. It is thus saturated with water bubbles. This moist steam is conducted thence through a nozzle 6 and a very narrow serpentine channel 7 formed in a body 7' that is preferably made of box wood. During their passage through the channel 7 the particles of water carried along by the steam are positively charged by their friction with the walls of the channel. To increase the friction the inside width of the channel is small and the channel has a serpentine form so as to cause the steam to continually change its direction of flow and to thus force it to brush against the channel walls. The polarity of the steam can be reversed by making it pass over oil, for example turpentine oil,

instead of condensed water in the vessel 4. Steam passes from the channel 7 through an exit nozzle 8 made of insulating material. The exit nozzle 8 and the body 7' may be 5 surrounded by a mantle 8' to prevent undue escape of heat. The serpentine channel 7 between the inlet nozzle 6 and the exit nozzle 8 also has the effect of causing the steam to flow out without the formation of eddies 10 therein so that disturbing collateral noises (hissing or swashing) are obviated. At the front end of the exit nozzle 8 there is a perforated metal body or grid 9 which is electrically charged as hereinafter described 15 by talking currents so that the intensity of the electrical charge of the grid fluctuates in the rhythm of the sound waves to be reproduced. The steam issuing from the grid 9 flows through a trumpet 10 which forms 20 a continuation of the path through the grid. From the trumpet steam passes into the external air. The shape of the trumpet 10 is such that condensed water may collect at its lowest part. This water may be conducted 25 back to the boiler 1 from time to time, this operation being performed manually or automatically by a device (not shown) provided for this purpose.

The sound reproduction device operates in 30 the following manner: The electric field or intensity of the charge of the metal grid 9 is proportional at every moment to the potential connected to the grid. If, as shown in the drawing, the potential connected to the 35 grid is positive, the steam will be repelled before and behind the grid due to the positive charge of the small water bubbles in the steam. The magnitude of the repelling forces fluctuates in accordance with the intensity of the electric field or the strength 40 of the potential applied. Consequently the amount of steam that passes through the sieve will not remain constant but it will be subjected to fluctuations of pressure that will 45 become noticeable in the exterior air in the form of sound waves.

In the device shown in the drawing the plastic phonogram impressed on the sound record or film 11 is used for the production 50 of talking currents in the following manner: A feeler is kept pressed by a spring against the film 11 which is moved continuously by a feed roller 12. The feeler 13 carries a grid-shaped electrode 13' arranged between 55 the anode 14 and the incandescent cathode 15 of a discharge gap. The cathode is heated by a heating battery 16. The circuit of the discharge gap leads from a battery 17 through a non-inductive high resistance 18. 60 An auxiliary potential from a battery 19 is applied to the grid-shaped auxiliary electrode 13'.

The fluctuations of potential that arise 65 in the discharge gap when the auxiliary electrode 13' is oscillated are communicated

through a conductor 20 to the grid or controlling electrode 22 of a thermionic valve 21 or amplifier. The thermionic valve 21 comprises, as well known, an incandescent cathode 23 which is heated by a heating battery 70 24 and an anode 25. Connected in the anode circuit, which receives current from a battery 28, is a high ohmic resistance 26. The anode 25 is connected by a wire 27 to the metal sieve or grid 9 so that the fluctuating potentials of the anode 21 are imparted to the 75 grid 9.

It is particularly important to maintain the pressure in the steam boiler as uniform as possible. This is accomplished by an electric regulator which comprises a mercury pressure gauge 29. When the steam pressure raises to a certain point the mercury, 80 30 closes an electric contact in a circuit containing a relay which regulates the heating 85 current.

The scope of the invention is not limited to the use of a steam electrifying device of the Armstrong type for it will also be feasible to employ an arrangement in which 90 the electrification of the water vapor or any other suitable fluid is not effected by friction, but by influence.

We claim:—

1. In a device for reproducing sounds, 95 means for producing a continuous current of gas or steam, and means in the path of said current for producing an electric field of changing intensity for controlling said current.

2. In a device for reproducing sounds, means for producing a continuous current of gas or steam, a perforated metal body in the path of said current, means for electrically 100 charging said gas or steam and means to vary said charging in rhythm to sound waves.

3. In a device for reproducing sounds, an electric heating means for converting water into a current of steam, means for electrically 110 charging said current, and means for producing an electric field of changing intensity for controlling said flow.

4. In a device for reproducing sounds, an electric heating means for converting water into a current of steam, means for electrically 115 charging said current, a perforated metal body in the path of said current, and means for variably electrically charging said body in the rhythm of sound waves.

5. In a device for reproducing sounds, an electric steam generator, a perforated metal body, a channelled body including a 120 condensed water container for conducting the steam to said perforated body, means for conducting condensed water from said container back to the steam generator, means for electrically charging the current of steam, and means for variably electrically 125 charging said perforated metal body in the rhythm of sound waves.

6. In a device for reproducing sounds, an electric steam generator, a perforated metal body, a nozzle leading to said perforated body, a channelled body including a condensed water container, a body with a narrow serpentine passage formed therein for conducting steam from said channelled body to said nozzle and perforated body, means for conducting condensed water from said

container back to the steam generator, means for electrically charging the current of steam, and means for variably electrically charging said perforated metal body in the rhythm of sound waves.

In testimony that we claim the foregoing as our invention, we have signed our names.

OTTO BOTHE.

LUDWIG SCHIFF.
